HIGH VOLTAGE EXPULSION FUSE

John W. Huffstutter, Forest Hills, Pa., assignor
to Westinghouse Electric & Manufacturing
Company, a corporation of Pennsylvania

Application September 20, 1930, Serial No. 483,236

13 Claims. (Cl. 200—127)

My invention relates to fuses and particularly to fuses of the high-voltage expulsion type.

One object of my invention is to provide a fuse for a high-voltage circuit with means whereby the fuse effectively extinguishes arcs of both low and high current values.

Another object of my invention is to provide a fuse of the above-mentioned type with gas-evolving plates that shall be decomposed by an arc to emit a gas that is turbulently passed through the arc stream.

A further object of my invention is to provide a fuse of the above-mentioned type with a casing within which plates of gas-evolving material are disposed adjacent to a fusible element that may be distorted by the pressure developed by arcs of high current value.

Heretofore, when a fuse of the expulsion type was selected for an electrical system, it was chosen of such capacity as to be capable of interrupting the maximum short-circuit current that the system was capable of developing. As such fuse devices could not be depended upon to interrupt arcs of low current value, considerable effort has been expended to develop a fuse that shall be capable of interrupting arcs of all current values. If a fuse device is selected of such rating as to interrupt arcs of low current value, the pressures developed when arcs of high current value are established will disrupt the fuse structure.

In practicing my invention, I overcome the above mentioned difficulties by providing flexible, gas-evolving plates within the fuse casing, about the fusible element. The plates fit snugly within the casing and are spaced apart a small distance in order to provide a slot within which an arc is established. The slot thus formed is capable of confining arcs of low current value and of evolving sufficient un-ionized gas from the plate material to effect arc extinguishment. When arcs of high current values are established within the slot, the pressure developed thereby so distorts the flexible plates that the slot is increased in width an amount proportional to the amount of energy developed in the arc.

My invention will best be understood by referring to the following specification, taken in conjunction with the accompanying drawing wherein:

Figure 1 is a sectional view, in elevation, of a fuse device embodying my invention;

Fig. 2 is a sectional view of the structure illustrated in Fig. 1, taken along the line II—II thereof, and

Fig. 3 is a view similar to Fig. 2 with the ex-

ception that the fuse element is shown as having been interrupted and the plates distorted by the ensuing pressure.

My invention comprises, in general, a casing 1 having its upper end sealed by a terminal cap 2 and its lower end provided with a clamping terminal 3. The upper end of the casing 1 is provided with a washer 4 having a central opening 5 through which a fusible element 6 extends and is held in fixed position against the top surface of the washer 4 by the cap 2 that is screwed upon the casing 1.

The clamping terminal 3 comprises a threaded ring 7 that is mounted on the outer surface of the casing 1 above its lower end. The lower surface of the ring 7 is tapered to conform to the tapered surface 11 on the clamping annular member 12 that is provided with threads on its upper inner surface. A shallow slot 13 is provided in the tapered portion of the ring 7 wherein the end of the fuse element 6 is inserted and clamped by the annular member 12.

The surface of the washer 4, within the casing 1, is provided with an extension 14. A pair of insulating plates 15 are attached to the extension 14 by means of rivets 16. The plates are flexible and are made of gas-evolving material, such as fiber, that is decomposed in the presence of an arc to emit and un-ionized gas.

The plates 15 are spaced apart a predetermined distance in order to provide a narrow slot within which the arc is confined and prevented from expanding laterally within the slots but is permitted to expand longitudinally therein.

In the copending application of Joseph Slepian Serial No. 208,686 filed July 27, 1927 and assigned to the assignee of the present invention, a fuse structure is disclosed wherein the arc is extinguished by being confined within a slot between insulating side walls whereon the deionization of the arc stream occurs. The theory of arc extinguishment disclosed in the Slepian application is applicable to the present invention, and the confinement of the arc by the side walls effects arc deionization on the surfaces thereof.

In addition to the extinguishing effect produced by the side walls, in close proximity to the arc, and in some cases far greater than it in magnitude, deionization is effected by the gas evolved from the confining walls. In the copending application of Joseph Slepian, Serial No. 423,660, filed Jan. 27, 1930 and assigned to the assignee of the present invention, an arc-extinguishing structure is disclosed wherein the decomposition

of the confining material is passed turbulently through the arc stream.

My present invention takes advantage of this additional deionizing effect by having the plates 15 made of materials that readily decompose in the presence of an arc. The gas thus evolved is confined between the plates 15 and is forced turbulently through the arc stream and out of the opening in the bottom of the casing. The hot ionized gases are thereby deionized or blown from within the casing and, upon the occurrence of a current zero, in the course of its alternating cycle, the arc will be prevented from becoming reinitiated.

When my fuse device is employed in direct-current circuits, the deionization of the arc stream by the blast of gas arising from the decomposition of the material causes the arc voltage to be greatly increased. This increased arc voltage causes the current to decrease, and with it, the rate of decomposition of material would diminish if the flexible plates did not close down upon the arc as the current diminished. By thus closing down, the gas evolution is kept large, even though the current is reduced, and thus the arc voltage is kept high. The width of the slot remains such as to have the arc voltage increased above the line voltage so that the current is continuously reduced to zero.

Fig. 2 discloses fibre plates 15 disposed on each side of the fuse element 6 in such manner as to be wedged within the casing 1 to thereby prevent them from moving laterally away from each other. The plates are constructed to have such strength as to resist the pressure developed by arcs of low current value, in order to retain the arcs in intimate contact with the surfaces of the plates to ensure sufficient evolution of un-ionized gas. When heavy-current arcs are established between the plates 15, the plates are distorted by the pressure developed thereby, as shown in Fig. 3. The distortion is proportional to the amount of gas evolved between the plates which is a function of arc current. The distortion reduces the rate of gas evolution and thus reduces the pressure which would otherwise develop to a dangerous degree. The reduction in gas evolution is not otherwise disadvantageous since, for the large currents, far more gas is evolved than is necessary for their extinction. My device, therefore, evolves the un-ionized gas in an amount that is only sufficient for the interruption of the current and thereby assures that the arc will be interrupted in the case of low currents without excessive pressures in the case of high currents.

It will be evident to those skilled in the art that other expedients than the use of flexible fibre plates may be resorted to in order to confine the arc within a space which increases in volume with the current interrupted, or to prevent a too great increase of gas-evolution with increase in current. Various devices for withdrawing material from proximity to the arc at large currents will be evident to those skilled in the art, and all such are within the scope of my invention.

While I have described and illustrated a single embodiment of my invention, it will be apparent to those skilled in the art that many changes, additions, omissions and substitutions may be made therein without departing from the spirit and scope of my invention, as set forth in the accompanying claims.

I claim as my invention:

75 1. A fuse device including a casing having two

80 closely spaced plates of gas-evolving material detached from said casing except adjacent one point and mounted therein in such manner as to constitute a slot within which an arc is drawn and extinguished.

85 2. An expulsion fuse having a casing and a pair of gas-evolving plates attached thereto at one point only and snugly mounted therein in such manner as to constitute a slot, and a fuse element disposed within said slot.

90 3. An expulsion fuse having a casing in the form of a round tube and a pair of substantially flat gas-evolving plates mounted therein to provide a slot the width of which may be increased by the pressure developed by an arc established 95 between the plates.

95 4. An expulsion fuse having a casing and a flexible plate mounted therein and forming at least a portion of one wall of a passage wherein an arc is established, the effective cross-sectional area of said passage being materially variable due to the flexure of said plate in such manner as to be a function of the pressure developed by the arc.

100 5. A fuse device including a tubular casing having two plates of gas-evolving material extending chordally thereacross so as to constitute a slot within which an arc is drawn and extinguished by the gas evolved from said gas-evolving material.

105 6. An expulsion fuse having a casing and a pair of flexible gas-evolving plates mounted therein to provide a slot the width of which may be materially increased by the pressure developed by an arc established between the plates, the gas evolved by the decomposition of the plates being proportional to the current present in the arc.

110 7. In an arc extinguishing device, closely spaced side walls comprising gas-evolving plates that are readily flexed by the pressure developed by an arc established between them.

115 8. In an arc extinguishing device, side walls forming a narrow slot for confining an arc, the side walls being movable by being flexed to materially increase the width of the slot by the pressure developed by the arc, the width to which the side walls are expanded being a function of 120 arc current.

125 9. In an arc extinguishing device, side walls separated by a narrow slot for confining an arc, the side walls being movable to change their shape materially to increase the width of the slot by the pressure developed by the arc, the width to which the side walls are expanded being a function of arc energy, the said walls being decomposable in the presence of an arc to evolve an un-ionized gas that passes turbulently through 130 the confined arc.

135 10. A fuse device including a casing having end terminals at least one of which is closed for sealing the end of the casing, a plate of flexible material attached at only one portion to the casing, 135 a fusible element within the casing and extending along said flexible plate for establishing an arc upon rupture thereof, the said arc evolving a gas that distorts said plate and passes turbulently through the arc stream.

140 11. In a circuit interrupter, means for causing an arc, a chamber closely confining said arc laterally, said chamber having a wall of a material which evolves an arc-extinguishing gas when acted upon by the arc and which is flexible permitting 145 expansion of said chamber to increase its cross-section materially in a direction transverse to the arc.

145 12. In a circuit interrupter, an elongated chamber closed on its sides and open at one end, means 150

for causing an arc in said chamber, said chamber having means therein for supplying a gas to extinguish the arc, and having flexible walls which increase the cross-section of the chamber materially in a direction transverse to the arc in response to the pressure of said gas.

13. In an expulsion fuse, a tubular insulating casing closed on its sides and open at one end, a pair of closely spaced plates having a narrow slot

therebetween, a fusible element extending longitudinally between said plates for causing an arc, said plates being of a material which decomposes when acted upon by the arc to give off a deionizing gas, and the cross-section of the space between said plates being variable in a material amount by said plates being bowed outwardly due to the pressure of said gas.
